UNITED STATES PATENT OFFICE.

FRANK ASHWORTH HOLT, OF ROCHDALE, AND GRINDROD KERSHAW, OF WHITWORTH,
ENGLAND.

THREAD OR YARN TENSION DEVICE AND CLEARER.

1,311,448.

Specification of Letters Patent. Patented July 29, 1919.

Application filed October 25, 1915. Serial No. 57,769.

To all whom it may concern:

Be it known that we, FRANK ASHWORTH HOLT, a subject of the King of the United Kingdom of Great Britain and Ireland, and resident of Neon Sun House, Whitworth Road, Rochdale, in the county of Lancaster, England, and GRINDROD KERSHAW, a subject of the King of the United Kingdom of Great Britain and Ireland, and resident of 62 Market street, Whitworth, in the county of Lancaster, England, have invented new and useful Improvements in Thread or Yarn Tension Devices and Clearers, of which the following is a specification.

15 This invention relates to the kind of apparatus for applying drag or tension to or cleaning yarn, thread, cord, twine or the like in which the material to be subjected to tension and cleaned is made to pass beneath and 20 to revolve a disk or the like by being made to pass between such disk or the like and a support beneath it.

This invention consists in a form of apparatus of the said kind more efficient and convenient than those heretofore provided in enabling the yarns, threads, cords, twine or the like subjected to drag or tension or cleaning to be wound at any speed requisite in any case under proper drag or tension and 30 cleaned without being subjected to excessive tension and consists further in advantageous expedients hereinafter to be indicated, hindering or checking such disks or like revolving parts from being revolved too freely and 35 obviating the too frequent or too protracted rise of disks or the like made to bear on yarn, thread, cord, twine or the like.

Hereinafter for simplicity the word "yarn" will be used instead of "yarn, thread, 40 cord, twine or the like" and the word "disk" will be used in the description and the claims to mean a disk, cup or other like part to be revolved by contact with yarn, thread, cord, twine or the like.

45 This invention is illustrated in the accompanying drawings by exemplifications. Figures 1 and 2 are respectively a side elevation partly in vertical section and a plan and Figs. 9 and 10 a vertical section and 50 plan of parts detached, illustrating one form of tension applying or yarn cleaning apparatus provided according to this invention and other forms are illustrated in Figs. 3-8 and

11-18 both inclusive in which Figs. 6, 12, and 14 are plan views, Figs. 15 and 17 are 55 plan views of the upper disks inverted and the rest are all vertical sections or vertical sections partly in side elevation to show parts more clearly and indicating how some of the expedients may be applied in forms 60 of tension device other than that shown by Figs. 1 and 2.

Figs. 1 and 2 serve also as an illustration of one way in which the parts provided according to this invention may be mounted 65 for use in the machines to which they are to be applied.

In the apparatus illustrated in Figs. 1 and 2, a disk *j* is mounted around and supported by the apex of a fixed pivot or projection *k* 70 carried by a fixed part *f* and is provided with a non-circular disk *a* mounted upon it so that yarn may be led between the disks *j* and *a*. The disk *j* is provided with an upwardly extending projection *p* in which 75 the hole to receive the pivot or projection *k* is formed and around which the disk *a* is placed.

According to this invention the one disk may be made with a projection shaped and 80 fitted to engage a corresponding space in the other of shape and size to permit the one disk to move athwart the axes of revolution relatively to the other while both disks are always compelled to revolve turn for turn together.

Further according to this invention a fixed projection or abutment of any kind may be placed near the disks so that one or each disk may swing against such projection or abutment in the lateral movement of such disk. The projection or abutment may be made to extend over the disks to hinder or prevent them or the upper one from being accidentally dislodged from their or its proper 95 working position and may be shaped so that the upper disk may be placed upon the projection or abutment before or while the lower disk is being put into or removed from its ordinary working position.

In Figs. 9 and 10, the sleeve of the disk *j* is shown as square in the upper part 1 and circular, to simplify manufacture, in the part 2 below the square part and the disk *a* mounted upon the sleeve *p* is provided with a 100 rectangular orifice *H* to receive the sleeve *p*

and of such width that the disk *a* will be turned with the disk *j* and long enough to allow the disk *a* to be moved diametrically upon the disk *j*. In Figs. 1, 2 and 9, a 5 projection *w*, omitted from Fig. 10, for parts below it to be shown, is illustrated as secured to the fixed part *f* and extending upward therefrom near the sides of the disks *j* and *a*.

In Figs. 1 and 9, the pivot or projection 10 *k* and the hole in the sleeve *p* to receive the pivot or projection *k* are indicated as cylindrical and fitting one another.

The fixed part *f* forms part of a bracket *A* which is provided with a hole to receive a 15 rod *B* and a set screw *A'* by which it is secured upon such rod *B*.

The bracket *A* is shaped so as to afford a notch *I* to act as a guide for yarn and also to afford a fence *J* extending around part 20 of the circumference of the disk *j* in order that yarn may be hindered from passing below the disk *j*. A wire curl *K* screwed into the bracket *A* is provided as a guide for yarn at the side of the disk *j* away from the notch 25 *I*. The bracket *A* and curl *K* form no part of this invention.

Yarn drawn through the notch *I* and the curl *K* or in the opposite direction will pass between the disks *j* and *a* and revolve them 30 and the friction of the yarn against the disks causes drag or tension to be applied to the yarn and effects the removal of loose matter from the yarn so cleaning it. The disk *j* with a sleeve *p* prevents dust from reaching 35 the bearing of the disk *j* on the pivot *k*. Should the yarn passing beneath the disk *a* revolve the disks *a* and *j* at a speed sufficient to throw the disk *a* out at one side it will arrive against the projection *w* and be 40 checked in its revolution and thus the disks *j* and *a* will be prevented from revolving too rapidly and allowing yarn to pass too freely between them. The projection *w* is provided with an arm extending over the 45 sleeve *p* of the disk *j* so as to prevent the disks from being accidentally removed from the pivot *k*.

The projection *w* is made so that it may be removed from the part *f* in any convenient manner when it is necessary or desirable 50 to remove the disk *a* or disk *j* from the pivot *k*. For example the projection *w* may be screwed into a screw threaded hole in the part *f*, as shown in Fig. 9.

55 The hole in the disk *j* may be made if desirable in any case a little larger than the pivot or projection *k* so that the disk *j* may move or wabble laterally in relation to and "bind" more readily upon the pivot or projection *k* so as to be checked in its revolution or the pivot *k* or the hole in the disk *j* to receive it or both of them may be made taper as for example in modes analogous to those hereinafter described in reference to 60 Figs. 7 and 8. The provision for lateral 65

movement or wabbling is preferably made greater at the bottom than at the top so that the upper part of the sleeve *p* may have less movement than the bottom.

Further according to this invention in 70 an apparatus comprising two disks the upper disk or the lower disk or both disks is or are made unsymmetrical or out of balance relatively to the axis about which it or they is or are made to revolve or a weight 75 or washer or two or more made unsymmetrical or out of balance relatively to the axis about which it or they is or are to be made to revolve may be provided to be applied in or on the upper disk whether or not the 80 upper disk or the lower disk or both is or are made unsymmetrical or out of balance.

Making a disk unsymmetrical or out of balance with relation to its axis of rotation or non-circular or weighting it with a weight 85 or washer which is unsymmetrical or out of balance with relation to its axis of rotation insures that any incipient increase in speed of revolution of the disk shall be accompanied by an increased tendency of the 90 disk to lateral movement causing, according to the construction adopted in any case, lateral movement of the disk or increased pressure of the disk against its support or, in the case of a disk mounted on another disk, 95 lateral movement of one or other disk or both or increased pressure of the one or other disk or both against its or their support or arrival of the disk or one or other disk against the stop if there be any provided for checking it from revolving and thus in any case the incipient tendency of the disk or disks to unduly rapid revolution is quickly checked.

The unsymmetrical or unbalanced form of 105 a disk or washer or weight may be brought about by any method by which the mass of the disk, washer or weight may be made unsymmetrical or unbalanced relatively to the axis about which it or the disk to which it 110 is applied may be made to revolve. Thus for example an unsymmetrical mass may be provided at one place or more or one part or more may be removed or the disk or washer or weight may be bent or indented. 115

An unsymmetrical weight or washer or two or more applied to a symmetrical or unsymmetrical disk may be used along with a symmetrical weight or washer or two or more and a symmetrical weight or washer 120 or two or more may be applied to an unsymmetrical disk.

In specially advantageous forms of disk made unsymmetrical or out of balance or provided with a washer or weight or two 125 or more made unsymmetrical or out of balance as aforesaid and made to revolve by the yarn forming in themselves part of this invention provision is made for some movement of part of the disk athwart its axis 130

either transversely to that axis or into positions oblique to one another so that the disk may revolve eccentrically or wabble or swing in revolving. The provision for this movement of the disk may be made for example by the hole in the disk or the hole to receive the spindle of the disk being larger than the part to be received in it or by the hole being taper while the part to be received in it is cylindrical or vice-versa or by the hole and the part to be received in it being of different tapers.

Ordinarily if a disk having a bearing in its upper part is to be allowed to move laterally or to wabble or swing in revolution provision or clearance to allow lateral movement is made in its lower part so that the position of its higher part does not much change.

If provision be made for a disk to move in the direction of its axis of revolution this provision may be accompanied by greater opportunity for the disk to be moved transversely or to become oblique to the part on or in which it is mounted so that in moving in one direction along that axis in use it may revolve more and more eccentrically. This may be effected by providing a conical or other taper pin or projection to receive a disk or providing a disk with a conical or other taper pin or spindle.

Fig. 3 illustrates an apparatus wherein the disk *a* is unsymmetrical, being made eccentric relatively to the pivot *b*, while the disk *j* is symmetrical and provided with an orifice *C* larger in diameter than the pivot *b*, so as to be movable laterally relatively to the pivot *b*.

Fig. 4 illustrates an apparatus wherein the disk *j* is unsymmetrical and the disk *a* is symmetrical.

The disk *a* is shown provided with weights or washers *o*.

In Fig. 5 two disks *a j* generally similar to the disks *a j* shown in Figs. 1 and 2 are illustrated as provided with two unsymmetrical weights or washers *o* applied in the disk *a* around the sleeve *l* thereof.

Fig. 6 illustrates a disk *a* made unsymmetrical by being indented at one side. Weights of a shape enabling them to be placed in the indented disk *a* may be employed if desirable to increase the pressure upon yarn passed beneath the disk *a*.

In Fig. 7 hereinafter further described a disk *a* made unsymmetrical by the wall being thicker at one side *q* of the disk *a* than at the other is illustrated as applied to a disk *j* which is symmetrical. In Fig. 8 also hereinafter further described a disk *j* made unsymmetrical by the wall being thicker at one side *r* of the disk *j* than at the other is illustrated having applied to it a symmetrical disk *a*.

In Figs. 5 and 7 the disk *a* is shown as

formed with a hole *H* a little larger than the sleeve *p* of the disk *j* so that the disk *a* may be moved laterally relatively to the disk *j* in being turned upon it.

In Fig. 7 the pivot *k* is shown as thicker 70 at the top and tapers downward while the hole to receive it in the sleeve *p* is cylindrical.

In Fig. 8 the pivot *k* is shown as cylindrical while the hole to receive it in the 75 sleeve *p* tapers from its mouth or entrance to the top.

In Figs. 7 and 8 it will be seen that the disks *j* having bearings in their upper parts the provision of clearance to allow lateral 80 movement is made in the lower parts so that the position of the higher parts does not much change.

Fig. 8 also shows a symmetrical weight 85 *o* in the disk *a*.

Figs. 11 and 12 illustrate a disk *j* generally similar to that shown in Fig. 8 but formed with three holes *t* for the escape of dirt or other matter separated from yarn. The holes *t* are separated by radial spokes 90 formed with rightangled edges which may scrape yarn brought against them.

Figs. 13 and 14 illustrate a disk *j* generally similar to that shown in Fig. 7 but formed with a hollow *u* around the sleeve *p* 95 so that yarn pressed against it shall bear against the circumferential parts *v* rather than against the central parts thereof, and with four holes *t* for the escape of dirt or other matter separated from yarn. The holes 100 *t* are separated by spokes which being below the hollow *u* do not receive contact of yarn passed between the disk *j* and the disk *a* used with it.

If desirable in any case to facilitate revolution by reducing the surface of contact a disk of a tension or yarn cleaning device formed or contrived in any of the ways hereinbefore described or in any combination of such ways may be provided with a 110 rib or projection or ribs or projections or recess or recesses in the part to be in contact with the surface on which it is to rest or the other disk as the case may be or the yarn to be subjected to tension or cleaned. 115 The disk used in any case may be beveled or rounded at the edges to facilitate the passage of yarn beneath or between it and another, each of the disks shown in the accompanying drawings being provided with 120 rounded edges.

Figs. 15 and 16 illustrate a disk *a* generally similar to that shown in Fig. 7 but furnished on its lower face with ribs or projections *y*, six being shown in Fig. 15 125 but for the sake of clearness only two in Fig. 16.

By way of example of the provision of recesses Figs. 17 and 18 illustrate a disk *a* generally similar to that shown in Fig. 7 130

but furnished in its lower face with recesses ϵ , six being shown in Fig. 17 but for the sake of clearness only two in Fig. 18.

An apparatus provided according to this invention may be provided with or employed along with any guide or guides requisite or convenient for guiding yarn to or from it.

Disks made or contrived according to this invention may be made of any suitable metal 10 or alloy of or glass or porcelain.

In any cases in which a washer or weight or two or more is or are to be applied to a disk with a central hole, the inner circumference of the disk is preferably provided with a rim or flange as in the cases illustrated in Figs. 5, 6 but in other cases in which a disk is provided with a central hole the inner circumference of the disk may be provided or not provided with a rim or 20 flange as may be considered desirable.

It is to be understood from the preceding description of the different disks provided according to this invention that different upper disks may be used with different lower 25 disks as may be desirable in the building up of tension applying or yarn cleaning apparatus or from time to time as may be desirable and that the provision for the application of a weight or washer is only essential 30 in cases in which such provision or such weight or washer is mentioned in the claims following.

Disks which are made unsymmetrical or out of balance as hereinbefore described, 35 especially if made capable of lateral movement or swinging or assuming positions oblique to one another, become checked in their revolution at a lower speed than disks which are symmetrical or balanced.

40 What we do claim as our invention and desire to secure by Letters Patent is:—

1. In a tension device, a support for a tension disk and a revoluble tension disk of unsymmetrical form carried thereby having 45 its mass unsymmetrical in relation to its axis of revolution and so tending to lateral movement in revolution and being made movable athwart such axis, substantially as hereinbefore described.

50 2. In a tension device, a support for tension disks, two revoluble tension disks carried thereby one of which is of unsymmetrical form and has its mass unsymmetrical in relation to its axis of revolution and so 55 tend to lateral movement in revolution and is made movable athwart such axis, substantially as hereinbefore described.

3. In a tension device, a support for tension disks, two revoluble tension disks of 60 unsymmetrical form carried thereby, each of which has its mass unsymmetrical in relation to its axis of revolution and so tends to lateral movement in revolution and is made movable athwart such axis, substantially as hereinbefore described.

4. In a tension device comprising a support for a revoluble tension disk and a revoluble tension disk carried thereby, a tension disk adapted to receive weighting means for adjusting the pressure of such disk 70 and weighting means applied to such disk and unsymmetrical in form and mass relatively to the axis of revolution of the disk when it is applied to such disk and so tending to lateral movement of the disk and 75 weighting means and also movable athwart such axis, substantially as hereinbefore described.

5. In a tension device comprising a support for a revoluble tension disk and a revoluble tension disk carried thereby, a tension disk which is adapted to receive weighting means for adjusting its pressure and is allowed movement athwart its axis of revolution and weighting means applied to such 80 disk and unsymmetrical in form and mass relatively to the axis of revolution of the disk when it is applied to such disk and so tends to lateral movement of the disk and weighting means in revolution and also 85 movable athwart such axis, substantially as hereinbefore described.

6. In a tension device comprising a support for revoluble tension disks and revoluble tension disks carried thereby, one disk which is adapted to receive weighting means for adjusting its pressure and weighting means applied to such disk and having its form and mass unsymmetrical relatively to the axis of revolution of the disk when it 100 is applied to such disk and so tending to lateral movement of the disk and weighting means in revolution and also movable 105 athwart such axis, substantially as hereinbefore described.

7. In a tension device comprising a support for revoluble tension disks and revoluble tension disks carried thereby, one disk which is adapted to receive weighting means for adjusting its pressure and is allowed movement athwart its axis of revolution and weighting means applied to such disk and having its form and mass unsymmetrical relatively to the axis of revolution of the disk when it is applied to such disk and so 110 tending to lateral movement of the disk and weighting means in revolution and also movable athwart such axis, substantially as hereinbefore described.

8. In a tension device comprising a support for a revoluble tension disk and a revoluble tension disk carried thereby, a tension disk which has its form and mass unsymmetrical in relation to its axis of revolution and is adapted to receive weighting 115 means for adjusting its pressure and weighting means applied to such disk and unsymmetrical in form and mass relatively to the axis of revolution and so tending to lateral movement of the disk and weighting means 120

125

and also movable athwart such axis, substantially as hereinbefore described.

9. In a tension device a support for a revoluble tension disk and a revoluble tension disk carried thereby, a tension disk which has its form and mass unsymmetrical in relation to its axis of revolution and is allowed movement athwart that axis and is adapted to receive weighting means for adjusting its pressure and weighting means applied to such disk and unsymmetrical in form and mass relatively to the axis of revolution and so tending to lateral movement of the disk and weighting means and also movable athwart such axis, substantially as hereinbefore described.
10. In a tension device a support for revoluble tension disks and two revoluble tension disks carried thereby and having one disk with its form and mass unsymmetrical in relation to its axis of revolution, one disk adapted to receive weighting means for adjusting its pressure and weighting means applied to such disk and unsymmetrical in form and mass relatively to the axis of revolution and so tending to lateral movement of the disk and weighting means and also movable athwart such axis, substantially as hereinbefore described.
11. In a tension device comprising a support for revoluble tension disks and two revoluble tension disks carried thereby and having one disk with its form and mass unsymmetrical in relation to its axis of revolution, one disk adapted to receive weighting means for adjusting its pressure and allowed movement athwart its axis of revolution and weighting means applied to such disks and unsymmetrical in form and mass relatively to the axis of revolution and so tending to lateral movement of the disk and weighting means in revolution and also movable athwart such axis, substantially as hereinbefore described.
12. In a tension device comprising a support for revoluble tension disks and two revoluble tension disks carried thereby each of which has its form and mass unsymmetrical in relation to its axis of revolution, one disk adapted to receive weighting means for adjusting its pressure and weighting means applied to such disk and unsymmetrical in form and mass relatively to the axis of revolution and so tending to lateral movement of the disk and weighting means in revolution and also movable athwart such axis, substantially as hereinbefore described.
13. In a tension device comprising a support for revoluble tension disks and two revoluble tension disks carried thereby each of which has its form and mass unsymmetrical in relation to its axis of revolution, one disk adapted to receive weights for adjusting its pressure and allowed movement athwart its axis of revolution and weighting

means applied to such disk and unsymmetrical in form and mass relatively to the axis of revolution and so tending to lateral movement of the disk and weighting means in revolution and also movable athwart such axis, substantially as hereinbefore described.

14. In a tension device of the character described comprising two revoluble disks, one disk with a projection shaped to engage a space in the other and the other with a space surrounding such projection and of shape and size to permit the one disk to move athwart the axis of revolution relatively to the other while both are always compelled to revolve turn for turn together, substantially as hereinbefore described.

15. In a tension device of the character described comprising two revoluble tension disks and having one disk non-circular, one disk with a projection shaped to engage a space in the other and the other with a space surrounding such projection and of shape and size to permit the one disk to move athwart the axis of revolution relatively to the other while both are always compelled to revolve turn for turn together, substantially as hereinbefore described.

16. In a tension device of the character described comprising two revoluble disks and an abutment to be touched by one of them, one disk with a projection shaped to engage a space in the other and the other with a space surrounding such projection and of shape and size to permit the one disk to move athwart the axis of revolution relatively to the other while both are always compelled to revolve turn for turn together, substantially as hereinbefore described.

17. In a tension device of the character described comprising two revoluble disks and an abutment to be touched by one of them, and having one disk non-circular, one disk with a projection shaped to engage a space in the other and the other with a space surrounding such projection and of shape and size to permit the one disk to move athwart the axis of revolution relatively to the other while both are always compelled to revolve turn for turn together, substantially as hereinbefore described.

18. In a tension device, a support for a fixed pivot, an upwardly directed fixed pivot on such support, an abutment on such support, a tension disk with a sleeve having a hole surrounding such pivot and resting upon its apex and having an upwardly directed projection shaped to engage a space in the other disk and a second tension disk mounted on the first and having a hole surrounding such projection and of size and shape to compel both disks to revolve turn for turn together and to permit the one disk to move athwart the axis of revolution relatively to the other and to touch the abutment, substantially as hereinbefore described.

19. In a tension device, a support for a fixed pivot, an upwardly directed fixed pivot on such support, a tension disk with a sleeve having a hole surrounding such pivot 5 and resting upon its apex and having an upwardly directed projection shaped to engage a space in the other disk and a second tension disk of non-circular form mounted on the first and having a hole surrounding such 10 projection and of size and shape to compel both disks to revolve turn for turn together and to permit the one disk to move athwart the axis of revolution relatively to the other and to touch the abutment, substantially as 15 hereinbefore described.

20. In a tension device, a support for a fixed pivot, an upwardly directed fixed pivot on such support, an abutment on such support, a tension disk with a sleeve having 20 a hole surrounding such pivot and resting upon its apex and having an upwardly di-

rected projection shaped to engage a space in the other disk and a second tension disk mounted on the first and with engaging means to be brought against the abutment 25 and a hole surrounding such projection and of size and shape to compel both disks to revolve turn for turn together and to permit the one disk to move athwart the axis of revolution relatively to the other and to 30 allow the engaging means to touch the abutment, substantially as hereinbefore described.

In testimony, that we claim the foregoing as our invention, we have signed our names in presence of two witnesses, this twelfth 35 day of October 1915.

FRANK ASHWORTH HOLT.
GRINDROD KERSHAW.
